US0D1051838S

(12) **United States Design Patent** (10) Patent No.: **US D1,051,838 S**
(45) Date of Patent: ** Nov. 19, 2024

(54) **SINGLE-SLOT TUBULAR CATHODE**

(71) Applicant: **Applied Materials, Inc.**, Santa Clara, CA (US)

(72) Inventors: **Bon-Woong Koo**, Andover, MA (US); **Frank Sinclair**, Hartland, ME (US); **Alexandre Likhanskii**, Malden, MA (US); **Svetlana Radovanov**, Brookline, MA (US); **Alexander Perel**, Danvers, MA (US); **Graham Wright**, Newburyport, MA (US); **Jay T. Scheuer**, Rowley, MA (US); **Daniel Tieger**, Manchester, MA (US); **You Chia Li**, Reading, MA (US); **Jay Johnson**, Gloucester, MA (US); **Tseh-Jen Hsieh**, Rowley, MA (US); **Ronald Johnson**, Gloucester, MA (US)

(73) Assignee: **Applied Materials, Inc.**, Santa Clara, CA (US)

(**) Term: **15 Years**

(21) Appl. No.: **29/818,782**

(22) Filed: **Dec. 10, 2021**

(57) **CLAIM**

The ornamental design for a single-slot tubular cathode substantially as shown and described.

DESCRIPTION

FIG. 1 is a first isometric view of a single-slot tubular cathode showing the new design;

FIG. 2 is a second isometric view thereof;

FIG. 3 is a top view thereof;

FIG. 4 is a bottom view thereof;

FIG. 5 is a first side view thereof;

FIG. 6 is a second side view thereof;

FIG. 7 is a first end view thereof; and,

FIG. 8 is a second end view thereof.

The broken lines illustrate the environmental structure and form no part of the claimed design.

1 Claim, 7 Drawing Sheets

Related U.S. Application Data

continuation-in-part of application No. 16/817,500, filed on Mar. 12, 2020, now Pat. No. 11,127,557.
